(57) **CLAIM**

The ornamental design for a card deck holder, as shown and
described.

DESCRIPTION

FIG. 1 is an isometric view of a card deck holder;
FIG. 2 is a front view thereof, wherein a rear view is a mirror
image of the front view;
FIG. 3 is a left-hand side view thereof, wherein a right-hand
side view is a mirror image of the left hand side view;
FIG. 4 a top view thereof; and,
FIG. 5 is a bottom view thereof.
